UNITED STATES PATENT OFFICE.

CHRISTEEENA R. WHITE, OF ASHEVILLE, NORTH CAROLINA.

HAIR-WAVING DEVICE.

Application filed July 28, 1927. Serial No. 209,054.

This invention relates to hair waving devices and more particularly to the construction of the pins employed in what is known as permanent wave apparatus.

An important object of the invention is to provide a device of this character which will enable the hair to be wound in much larger strands than may be ordinarily employed.

A further object of the invention is to provide a pin of such construction that the hair adjacent the head is given a relatively large wave effect, while the end portions may be formed as ringlets.

A still further object of the invention is to provide a device of this character which may be readily and cheaply constructed and which will be efficient in service.

These and other objects I attain by the construction shown in the accompanying drawings, wherein for the purpose of illustration is shown a preferred embodiment of my invention and wherein:—

Figure 1 is a side elevation of a hair waving pin constructed in accordance with my invention;

Figure 2 is an edge elevation thereof;

Figure 3 is a section on the line 3—3 of Figure 1;

Figure 4 is an end elevation of the pin.

Referring now more particularly to the drawing, the pin comprises two co-axial sections 10 and 11 which are integrally connected to one another. The section 10 is ovate in cross section, while the section 11 is circular and of a diameter approximately equal to the diameter of the section 10 upon its minor axis. At the junction of these sections, the section 10 is gradually reduced at 12, so that it merges into the circular section without the formation of any abrupt shoulders or sharp corners which might cause damage to the hair. At its free end, indicated at 13, the section 10 similarly merges into an axial circular prolongation 14, which has in its end a slot 15, such as is ordinarily provided for the reception of a tying thread, whereby the lock of hair which is to be wound upon the pin is secured thereto. These pins may be employed in the usual heaters of hair waving apparatus (not herein disclosed).

In the use of the device, a lock of hair, after it has been attached by a thread wound about the lock and in the slot 15, is wound upon the section 10, with the exception of its

extremity. This extremity is wound upon the section 11, with the result that it will be much more tightly waved than the major portion of the lock.

A device of this character has been found to give excellent results in service and to greatly expedite the work of winding the hair, due to the fact that larger locks may be wound thereon. It will, of course, be obvious that the pins, as illustrated, may be made in different sizes and the relative lengths of the sections 10 and 11 varied to suit the requirements of the user.

Since the construction hereinbefore set forth is capable of a certain range of change and modification without materially departing from the spirit of the invention, I do not limit myself to such specific structure except as hereinafter claimed.

I claim:—

1. A pin for use in hair waving apparatus comprising a body substantially ovate in cross section and having at one end a short axial extension circular in cross section, said axial extension being slotted.

2. A pin for use in hair waving apparatus comprising a body substantially ovate in cross section and having at one end a short axial extension circular in cross section, said axial extension being slotted, the opposite end of the body having a relatively long axial extension which is likewise circular in cross section.

3. A pin for use in hair waving apparatus comprising a body substantially ovate in cross section and having at one end a short axial extension circular in cross section, said axial extension being slotted, the opposite end of the body having a relatively long axial extension which is likewise circular in cross section, said body merging into said extension.

4. A pin for use in hair waving apparatus comprising a body substantially ovate in cross section and having at one end a short axial extension circular in cross section, said axial extension being slotted, the opposite end of the body having a relatively long axial extension which is likewise circular in cross section, the last named axial extension having a diameter approximately the same as the thickness of the body upon its minor axis.

5. A pin for use in hair waving apparatus

comprising a body substantially ovate in cross section and having at one end a short axial extension circular in cross section, said axial extension being slotted, the opposite end of the body having a relatively long axial extension which is likewise circular in cross section, said body merging into said

extension, the last named axial extension having a diameter approximately the same as the thickness of the body upon its minor axis. 19

In testimony whereof I hereunto affix my signature.

CHRISTEEENA R. WHITE.
